UNITED STATES PATENT OFFICE

1,958,282

RADIO APPARATUS

Ernest T. Tregenza, Coventry, England, assignor
to General Electric Company, a corporation
of New York

Application February 7, 1933, Serial No. 655,659
In Great Britain February 13, 1932

5 Claims. (Cl. 116—124.3)

My invention relates to radio apparatus and more particularly to an indicator for a multi-range tuning or switching device.

My invention has for its object to provide a simple indicator in combination with the multi-range tuning and switching device for indicating the proper scale and the frequency range corresponding to the switching operation performed by the operator.

10 In accordance with my invention, I provide a dial fixed to the variable tuning element of the radio apparatus, and having a plurality of scales, one for each of the frequency ranges over which the radio apparatus operates by adjustment of the variable tuning element. An additional dial mechanically connected to the switching mechanism of the apparatus is mounted with respect to the first dial so as to expose only that scale which is to be used in conjunction with the particular connections in the radio apparatus established by the switching means. The switching mechanism may have a plurality of positions corresponding to the different frequency bands and may include an "off" position, and in the 15 case of a receiver, a phonograph position. The change-over switch when operated, moves the additional dial so that the proper scale is exposed or appropriate words indicate the condition of the receiver when the dial completely 20 covers up the first scale.

The novel features which I believe to be characteristic of this invention are set forth with particularity in the appended claims. My invention itself, however, both as to its organization 25 and method of operation, together with further objects and advantages thereof, will be better understood by reference to the following description taken in connection with the accompanying drawing in which Fig. 1 shows in elevation one embodiment of my invention and Fig. 40 2 shows in elevation the application of my invention to a different type dial.

Referring to Fig. 1 of the drawing, I have illustrated therein a portion of the radio apparatus cabinet 1 provided with an aperture 2 through which both the tuning dial 3 and the switching dial 4 are visible. The tuning dial 3 is mounted upon the shaft 5 of a suitable variable tuning element such as a variometer or 45 condenser. The switching mechanism of the radio apparatus is connected to a shaft 6 which is also provided with a sprocket 7 over which a chain operates to cause rotation of the switching dial 4. It is of course understood that the 50 switching dial may be operated by any other

suitable mechanical means so that the switching dial will indicate the position of the switch attached to the shaft 6. The tuning dial 3 is provided with a plurality of series of indicia or scales representing the resonant frequency of the apparatus so that each one of the series of indicia indicates the frequency range over which the tuning element attached to the shaft 5 will operate. The switching dial 4, which is mounted between the tuning dial 3 and the aperture 2 of the apparatus cabinet 1, is preferably opaque and is provided with apertures so that only one of the scales on the tuning dial 3 will be visible at one time. The switching dial 4 is arranged to permit observation of the tuning dial 3 only when the radio apparatus is energized, and when the apparatus is deenergized the dial 4 obscures the view of the tuning dial 3, and the legend "off" appears in the aperture 2 of the cabinet 1. Suitable legends such as "Short wave" and "Long wave" may be placed near the respective apertures in the switching dial 4 to indicate the frequency range at which the apparatus operates with the particular setting of the switching mechanism.

A suitable light may be provided to illuminate the scales. The words or notations on the switching dial may be made transparent so that the light will show through or they may be engraved or painted in different colors.

The arrangement disclosed in Fig. 2 shows the application of my invention to radio apparatus employing a drum dial. The shaft 5 of a tuning element is provided with a drum dial 8 which has a plurality of series of indicia or scales thereon so that each scale covers one of the frequency ranges through which the tuning element will operate. The switching dial 4 is arranged at right angles to the drum dial 8 and interposed between the dial and the aperture 2 in the cabinet 1 of the radio apparatus. Although I have only shown two scales on each dial, it is of course understood that any number of scales may be employed and that the switching dial 4 may be of sufficient size so as to have a plurality of apertures equal in number to the number of scales on the tuning dial.

My invention has the advantage that it is possible to ascertain the condition of the radio apparatus by looking at the indication present at a single aperture in the apparatus cabinet. Thus it is not necessary to observe a plurality of dials located at remote points on the cabinet. My invention has the further advantage that the pos-

sibility of confusion is avoided by permitting only one scale to be visible at any time.

While I have shown and described my invention in connection with certain specific embodiments it will, of course, be understood that I do not wish to be limited thereto, since it is apparent that the principles herein disclosed are susceptible of numerous other applications, and modifications may be made in the instrumentalities employed without departing from the spirit and scope of my invention as set forth in the appended claims.

What I claim as new and desire to secure by Letters Patent of the United States, is:

- 15 1. In multi-range radio apparatus having adjustable frequency-range control means, the combination of a dial having a plurality of series of indicia, each of said series of indicia representing one frequency range of said radio apparatus, and means including a second rotatable dial cooperating with said first dial in accordance with the instant adjustment of said frequency-range control means whereby the proper series of indicia is exposed.
- 20 2. The combination, in multi-band radio apparatus having frequency-band adjusting means, a dial having a plurality of series of indicia, each of said series of indicia representing one frequency band of said radio apparatus, and means including a second rotatable dial cooperating with said first dial in accordance with the adjustment of said frequency-band adjusting means whereby the unused portions of said first dial are obscured.

3. The combination, in multi-range radio apparatus having means for changing the frequency range of said apparatus, of a dial having a plurality of series of indicia representing the resonant frequency of said apparatus, a second dial cooperating with said first dial, means for changing the angular position of said second dial in accordance with the changes in the frequency range of said radio apparatus whereby the unused portions of said first dial are obscured.

4. The combination, in multi-range radio apparatus having means for changing the frequency of said apparatus, a dial having a plurality of series of indicia, a second dial provided with apertures cooperating with the indicia of said first dial, means for actuating said second dial in accordance with changes in the operating condition of said radio apparatus whereby the appropriate portion of said first dial becomes visible.

5. The combination, in multi-range radio apparatus having switching means for changing the frequency-range and for energizing and de-energizing said apparatus, a dial having a plurality of series of indicia, a second dial provided with apertures cooperating with the respective indicia of said first dial, means for actuating said second dial in accordance with changes in the operating condition of said radio apparatus as determined by said switching means whereby the appropriate portion of said first dial is visible when said apparatus is energized and said first dial is obscured when said apparatus is deenergized.

ERNEST T. TREGENZA.
